UNITED STATES PATENT OFFICE.

FRANCIS W. GOODYEAR, OF SPRINGFIELD, MASSACHUSETTS.

TOY SPRING-GUN.

SPECIFICATION forming part of Letters Patent No. 332,892, dated December 22, 1885.

Application filed May 1, 1885. Serial No. 164,112. (No model.)

To all whom it may concern:

Be it known that I, FRANCIS W. GOOD-
YEAR, of Springfield, in the county of Hamp-
den and State of Massachusetts, have invented
5 a new and Improved Toy Gun, of which the
following is a full, clear, and exact descrip-
tion.

This invention relates to certain new and
useful improvements in that class of toy guns
10 in which the dart or arrow is thrown by an
elastic band or cord.

The invention consists in the construction
and arrangement of parts, as will be herein-
after fully described and claimed.

15 Reference is to be had to the accompanying
drawings, forming part of this specification,
in which similar letters of reference indicate
corresponding parts in all the figures.

Figure 1 is a longitudinal view of my im-
proved toy gun, parts being broken out. Fig.
20 2 is a plan view of the same. Fig. 3 is a plan
view, the arrow being in position for firing.
Fig. 4 is an enlarged detail sectional view of
the trigger, arrow, &c.

25 The barrel A is secured on the stock B,
and the said barrel has a longitudinal groove,
A', in its top. The trigger C is pivoted in a
slot in the barrel, and has its upper end, which
30 projects slightly from the groove in the bar-
rel, beveled, and the other or lower end is
connected by a wire, D, with the trigger-lever
E, pivoted in the stock. Directly behind the
trigger a block, F, having a longitudinal bore
35 or aperture, is secured on the top of the bar-
rel. An elastic cord or band, G, is secured
to the barrel at the muzzle end, and is passed
around the rear or butt-end of the block F.

40 A spiral spring, H, surrounding the wire D,
rests against the trigger C and presses the
upper end upward. The arrow J is provided
with a head, K, at its front end, and behind
the head with a collar, L, the rear side of
45 which is beveled. The arrow is placed in the
groove of the gun-barrel, its rear end being
passed into the bore of the block, and resting
against the elastic cord G. By pressing the
arrow toward the stock the elastic cord is
50 stretched, and when the collar L arrives at
the beveled end of the trigger C the same
catches on the collar, as shown in Fig. 4,
whereby the gun is cocked, the elastic cord

being stretched, as shown in Fig. 3. By
pulling the trigger-lever the upper end of the
trigger C is moved down, and the arrow is re-
leased, and is thrown forward by the elastic 55
cord, which contracts very forcibly. When
the gun is cocked ready for firing, the arrow
cannot slide out in whatever position the gun
may be. The block F acts as a stop or check
for the elastic cord G, which is forcibly 60
brought in contact with the rear end of the
said block when the gun is fired. Pistols can
be constructed in the same manner, and in
that case the trigger is operated direct, and
the trigger-lever and intermediate wire are 65
dispensed with. The block F has notches in
its rear end for receiving the elastic cord, and
the rear end of the arrow is notched.

I reserve the right to claim my arrow in a
separate application. 70

Having thus described my invention, what I
claim as new, and desire to secure by Letters
Patent, is—

1. In a toy gun, the combination, with a
barrel, of the apertured block F, secured on 75
the top of the barrel, the aperture in said
block being parallel with the length of the
barrel, the elastic band G, fastened to the gun
at or near the muzzle end and passed around
the rear end of the block, the trigger C, pivo- 80
ted in the barrel in front of the above-men-
tioned block F, the wire D, having its front
end connected with the trigger, and the trig-
ger-lever E, to which the rear end of the
wire D is connected, substantially as herein 85
shown and described.

2. The toy gun having a grooved barrel, a
block, F, apertured parallel with the groove
in the barrel, the trigger C in front of the
apertured block, the trigger-lever E, connected 90
with the trigger, and the elastic G, secured to
the muzzle end of the barrel and passed
around the rear end of the apertured block, in
combination with the arrow J, having a col-
lar adjacent to the rear of its head, whereby 95
when in place in the gun the collar and trig-
ger will engage when the rear end of the ar-
row is passed through the apertured block to
engage the elastic, substantially as set forth.

3. The toy gun having the apertured block 100
F, secured to the barrel in advance of its
breech, the spring-operated trigger C, having

its front end beveled, as described, the trigger-lever connected therewith, and the elastic G, secured to the muzzle end of the gun and passed around the rear end of the apertured block, in combination with an arrow having a collar adjacent to the rear of its head, said collar being beveled at its rear edge, whereby when the arrow is passed through the aper-

tured block the beveled collar will depress the beveled trigger and be engaged and held to thereby, substantially as set forth.
